UNITED STATES PATENT OFFICE.

MARQUIS J. TODD, OF CORNING, ASSIGNOR TO THE PITTS AGRICULTURAL WORKS, OF BUFFALO, NEW YORK.

HARROW.

SPECIFICATION forming part of Letters Patent No. 446,105, dated February 10, 1891.

Application filed June 28, 1890. Serial No. 357,057. (No model.)

To all whom it may concern:

Be it known that I, MARQUIS J. TODD, of Corning, in the county of Steuben, in the State of New York, have invented new and useful Improvements in Harrows, of which the following, taken in connection with the accompanying drawings, is a full, clear, and exact description.

My invention relates to improvements in harrows of the particular class in which the harrow-tooth is pivotally supported on the frame, and has for its object the production of a simple, strong, effective, and durable construction of harrow which is manufactured at a minimum cost of expense and presents a maximum degree of efficiency; and to this end my invention consists, essentially, in a harrow-frame having its bars disposed in zigzag form and provided at intervals with bearing-faces for supporting the teeth, tooth-supports having one extremity pivotally supported upon said frame-bars and the other extended downwardly beneath the same, and a spring-tooth secured to said downward extension; and the further object of my invention is the elevation of the harrow-frame throughout its entire length by means of pivoting tooth-supports projecting downward below the frame and carrying broad flat shoes for wearing-surface and providing runners or frictional planes for the carrying of the harrow; also, by securing tooth at lower end of pivoting tooth support or runner the draft is maintained at a lower plane and nearer its working end, thus lessening largely the leverage upon lower tooth-fastener and preventing frame tipping forward, as in a springing tooth curved downward from a higher plane or support.

The invention also consists in a clip-plate interposed between the harrow-frame bar and the upper extremity of the tooth-support, in a clip-plate for securing the tooth to the lower extremity of the tooth-support, and in the detail construction and arrangement of the parts, all as hereinafter more particularly described, and pointed out in the claims.

In describing this invention reference is had to the accompanying drawings, forming

a part of the specification, in which like letters indicate corresponding parts in all the views.

Figure 1 is a perspective of my improved harrow-frame, illustrating the general construction and arrangement thereof. Fig. 2 is an enlarged perspective of a single tooth and a detached portion of the frame. Fig. 3 is a vertical sectional view, showing in cross-section the frame-bars, clip-plates secured to said bars, the tooth-support, the tooth and its clip-plate. Fig. 4 is a vertical sectional view taken at right angles to the plane of Fig. 3, with the tooth-support shown in full. Fig. 5 is an elevation of the clip-plate mounted on the frame, and Fig. 6 is a perspective of the tooth clip-plate.

A represents the harrow-frame, composed of frame-bars *a*, disposed in zigzag form and provided at intervals with bearing-faces *a'*, from which the harrow-teeth *B* are supported.

As illustrated, the frame-bars are formed rectangular in cross-section, and are arranged with their narrow edges upward; but it will be understood that they may be of any other desirable form and construction, and may be arranged in any other suitable manner.

C represents the tooth-support pivotally supported upon the bearing-faces *a'* of the frame-bars by the clip-plate *D* interposed between said support and bars.

As illustrated, the clip-plate *D* is provided on its outer face with a slot *d*, adapted to receive the frame-bar and support the clip-plate, and at its inner face with an annular bearing *d'*, here shown as consisting of an annular projecting tongue.

The preferable manner of supporting the tooth-support *C* consists in providing its upper extremity *C'* with an annular bearing *c*, adapted to engage the bearing *d'* of the clip-plate *D*. As illustrated, this annular bearing *c* consists of a ring of slightly-greater diameter than the annular tongue *d'* for enabling the same to encircle said tongue.

E represents a bolt for securing the tooth-support *C* to the clip-plate *D*, and, as illustrated and preferably constructed, this bolt, in order to cheapen the cost of the harrow

and simplify its construction, in addition to securing the tooth-support to the clip-plate, secures said clip-plate to the seats or faces a' of the harrow-frame bars. It will be noted, 5 however, that as the center of the upper extremity C' of the tooth-support is preferably open the securing of the tooth-support to the former clip-plate D is effected by the frictional contact of the annular bearings provided upon the separate parts, and in order 10 to render this frictional contact more certain and strong the said annular bearings are preferably formed tapering in cross-section, whereby when the bolt E is tightened the 15 parts wedge together.

The lower extremity C^2 of the tooth-support C extends downwardly beneath the harrow-frame, and is provided with a tooth-secur- 20 ing face C^3 , to which is secured the spring-tooth B . This securing-face C^3 is preferably disposed in a curved plane with its rear extremity c' upturned in a sharper curve than the forward portion thereof.

In order to lighten the tooth-support, the 25 portion thereof interposed between the annular bearing c and the tooth-supports C^3 consists of an open web, which also, from its peculiar construction, affords great strength and rigidity. Moreover, this opening between 30 the extremities of the tooth-support is particularly advantageous, since it permits the tooth to be secured to the tooth-support with a single bolt, as its lower face forms a seat for the nut on the bolt G .

35 The spring-tooth B is preferably secured to the face C^3 of the tooth-support by means of a clip-plate F of desirable form, size, and construction to effect the desired result, and preferably sufficiently thick in cross-section to 40 withstand considerable wear.

The upper face of the tooth clip-plate F is provided with a recess F' , adapted to receive the securing extremity b of the spring-tooth B , and formed with side walls F' , lapping 45 upon the edges of the securing-face C^3 of the tooth-support for preventing side movement of the clip-plate when operatively mounted. The end motion of the tooth is prevented by shoulder f , against which rests the rear of the 50 securing extremity b .

In order to prevent the end motion of the clip, I provide upon the tooth-support a shoulder c^2 , (here shown as a round pin,) and upon the tooth clip-plate F a shoulder f' , of suitable form to engage the aforesaid shoulder c^2 . 55

The tooth clip-plate is securely clamped against the tooth by means of a bolt G , which preferably passes through said clip-plate tooth and securing-face C^3 and firmly and rigidly 60 secures the tooth to its support C .

When for the various purposes it is desired to adjust the tooth of my improved harrow, the bolt E is slightly loosened and the tooth-support is then swung to the desired position, 65 whereupon the free extremity b' of the tooth swings downward. This particular form of adjustment is very advantageous and desir-

able, since the tooth is rigidly secured upon a support, and that support is partially rotated to adjust the tooth, thereby obviating the necessity of loosening the tooth from the surface to which it is secured. Moreover, as the tooth is secured at a point considerably below the harrow-frame a slight movement of the tooth-support effects a greater amount of movement of the extremity b' of the tooth, and consequently the desired adjustment is occasioned with a very slight degree of movement of the tooth-support. Moreover, by securing the tooth beneath the harrow-frame I am enabled to form the upper extremity of the tooth-support of less width than the tooth, and thus approximate the harrow-bars closer together and form a more rigid and effective construction of frame. 85

A further advantage derived from my improved form of tooth-support, which, it will be noted, extends a considerable distance below the frame, is that but little friction is occasioned when using the harrow, since the same rides upon the clip-plates F , which are preferably curving, and that thereby all obstructions—as stones, quack, &c.—pass beneath the harrow-frame to the rear thereof, thus obviating all clogging of the harrow. It 90 will also be noted that the wear upon the securing extremity b of the tooth is prevented by the tooth clip-plates, and it will be readily understood that when worn these plates can be replaced with new ones, thereby greatly 100 increasing the life of the harrow and rendering the same practically indestructible by friction when in operation. This particular form of harrow is also very light from the peculiar construction of the tooth-supporting 105 device, and is strong and effective in use.

The operation of my invention will be readily perceived from the foregoing description, and it will be understood that the same may be somewhat varied from the described form 110 and construction without departing from the spirit of my invention.

Having thus fully described my invention, what I claim as new, and desire to secure by Letters Patent, is—

1. In a harrow, the combination of a frame-bar, a tooth-support having one extremity pivotally supported on said frame-bar and the other extremity extended downwardly beneath the frame-bar and adapted to rest upon the ground for forming a support for the frame, and a spring-tooth having one extremity secured to said downwardly-extending extremity of the tooth-support and the other extremity bent upwardly and then downwardly beneath the lower extremity of said support, whereby the depth of cut is regulated, substantially as and for the purpose specified. 120

2. In a harrow, the combination of a frame composed of zigzag frame-bars, a tooth-support having one extremity pivotally supported between contiguous angles of adjoining frame-bars, and the other extremity ex- 130

tended downwardly beneath the frame-bars and adapted to rest upon the ground for forming a support for the frame, and a spring-tooth formed of greater width than the upper extremity of said tooth-support, and having one extremity secured to said downwardly-extending extremity of the tooth-support and the other extremity bent upwardly and then downwardly beneath the lower extremity of said support, whereby the depth of cut is regulated, substantially as described and shown.

3. In a harrow, the combination of a frame-bar, a tooth-support having one extremity pivotally supported on said frame-bar and the other extremity extended downwardly beneath the frame-bar and adapted to rest upon the ground for forming a support for the frame, a spring-tooth having one extremity secured to said downwardly-extending extremity of the tooth-support, and a clip-plate beneath said extremity of the tooth for preventing wear thereupon, substantially as specified.

25 4. In a harrow, the combination of a frame composed of zigzag frame-bars, a tooth-support having one extremity pivotally supported between contiguous angles of adjoining frame-bars and the other extremity extended downwardly beneath the frame-bars and adapted to rest upon the ground for forming a support for the frame, a spring-tooth having one extremity secured to said downwardly-extending extremity of the tooth-support and the other extremity bent upwardly and then downwardly beneath the lower extremity of said support, whereby the depth of cut is regulated, and a clip-plate beneath said extremity of the tooth, substantially as and for the purpose described.

35 5. In a harrow, the combination of a frame-bar, a pair of clip-plates having one face supported on said bar, a tooth-support having one extremity supported on the opposite face of said clip-plate and having its opposite extremity extending downwardly beneath said frame-bar and adapted to rest upon the ground for forming a support for the frame, and a spring harrow-tooth having one extremity secured to said downwardly-extending extremity of the tooth-support and the other extremity bent upwardly and then downwardly beneath the lower extremity of said support, whereby the depth of cut is regulated, substantially as and for the purpose specified.

45 6. In a harrow, the combination of a frame-bar, a pair of clip-plates having one face supported on said bar, a tooth-support having one extremity supported on the opposite face of said clip-plate and having its opposite extremity extending downwardly beneath said frame-bar and adapted to rest upon the ground for forming a support for the frame, a spring-tooth having one extremity secured to said downwardly-extending extremity of

the tooth-support, and a clip-plate beneath said extremity of the tooth for preventing wear thereupon, substantially as set forth.

7. In a harrow, the combination of a frame-bar composed of zigzag frame-bars, clip-plates between the contiguous angles of adjoining frame-bars and supported thereon, a tooth-support having one extremity pivotally supported by said clip-plates and the other extremity extended downwardly beneath the frame-bars and adapted to rest upon the ground for forming a support for the frame, and a spring-tooth having one extremity secured to said downwardly-extending extremity of the tooth-support and the other extremity bent upwardly and then downwardly beneath the lower extremity of said support, whereby the depth of cut is regulated, substantially as described.

8. In a harrow, the combination of a frame-bar composed of zigzag frame-bars, clip-plates between the contiguous angles of adjoining frame-bars and supported thereon, a tooth-support having one extremity pivotally supported by said clip-plates and the other extremity extended downwardly beneath the frame-bars and adapted to rest upon the ground for forming a support for the frame, a spring-tooth having one extremity secured to said downwardly-extending extremity of the tooth-support, and a clip-plate beneath said extremity of the tooth, substantially as specified.

9. In a harrow, the combination of a frame-bar, a pair of clip-plates having one face secured to said frame-bar, an annular bearing upon the other face of said clip-plate, a tooth-support having one extremity provided with an annular bearing for engaging the annular bearing of the clip-plate and having its opposite extremity extended downwardly beneath the frame-bar and adapted to rest upon the ground for forming a support for the frame, a bolt for securing said tooth-support to said clip-plate, and a spring-tooth secured to the lower extremity of said tooth-support, substantially as described.

10. In a harrow, the combination of a frame-bar, a tooth-support having one extremity pivoted on said frame-bar and the other extended beneath the frame-bar and formed with a lower engaging-face disposed in a curved plane, and a tooth having one extremity secured to said face and the other bent upwardly and then downwardly beneath said face, substantially as described.

11. In a harrow, the combination of a frame-bar, a tooth-support having one extremity pivotally supported on said frame-bar and the other extremity extended downwardly beneath the same for forming a support for the frame, a lower engaging-face on said projecting extremity of the tooth-support, a tooth having one extremity secured to said lower engaging-face and the other bent downwardly beneath the same, and a clip-plate secured beneath the former extremity of the tooth

and formed with its lower face disposed in a curved plane, substantially as specified.

12. In a harrow, the combination of a frame-bar, a tooth-support having one extremity pivotally supported on said frame-bar and the other extremity extended downwardly beneath the same for forming a support for the frame, a lower engaging-face on the lower extremity of the tooth-support, an opening in the tooth-support above said face, a tooth mounted upon the engaging-face, and a clamp for securing said tooth to the support, said clamp having its upper extremity mounted in said opening in the tooth-support, substantially as set forth.

13. In a harrow, the combination of a frame-bar, a pair of clip-plates supported on the frame-bar, an annular tongue provided upon the adjacent face of one of said plates, a tooth-support having an annular ring for engaging said tongue, a bolt for securing together said tooth-support and plates, and a spring-tooth secured to said tooth-support, substantially as described.

14. In a harrow, the combination of zigzag frame-bars, clip-plates between the contiguous angles of adjoining frame-bars and secured thereto, an annular tongue provided upon the adjacent faces of said plates, a tooth-support having an annular ring for engaging said tongues, a bolt for securing said tooth-support to said plates, and a spring-tooth secured to said tooth-support, substantially as specified.

15. In a harrow, the combination of zigzag frame-bars, clip-plates between the contiguous angles of adjoining frame-bars, annular bearings provided on the adjacent faces of said clip-plates, a tooth-support having one extremity provided with an annular bearing for engaging the bearings upon the clip-plate, and having its opposite extremity extended downwardly beneath said frame-bars, a bolt for securing said tooth-support to said plate, and a spring-tooth secured to the lower ex-

tremity of said tooth-support, substantially as set forth.

16. In a harrow, the combination of zigzag frame-bars, clip-plates between the contiguous angles of adjoining frame-bars, annular bearings provided on the adjacent faces of said clip-plates, a tooth-support having one extremity provided with an annular bearing for engaging the bearings upon the clip-plate, and having its opposite extremity extended downwardly beneath said frame-bars, a bolt for securing said tooth support to said plate, a spring-tooth having one extremity secured to said downwardly-extending extremity of the tooth-support, and a clip-plate beneath said extremity of the tooth, substantially as and for the purpose described.

17. In a harrow, the combination of zigzag frame-bars, clip-plates between the contiguous angles of adjoining frame-bars, annular bearings provided on the adjacent faces of said clip-plates, a tooth-support having one extremity provided with an annular bearing for engaging the bearings upon the clip-plates, and having its opposite extremity extended downwardly beneath said frame-bars, a bolt for securing said tooth-support to said plates, a shoulder provided on the lower extremity of said tooth-support, a spring-tooth having one extremity secured to said downwardly-extending extremity of the tooth-support, a clip-plate beneath said tooth, and a shoulder on said clip-plate for engaging the shoulder of the tooth-support and preventing end motion of said clip-plate, substantially as and for the purpose set forth.

In testimony whereof I have hereunto signed my name, in the presence of two attesting witnesses, at Buffalo, in the county of Erie, in the State of New York, this 14th day of May, 1890.

MARQUIS J. TODD.

Witnesses:

HARRY HICKMAN,
S. G. VAN ARNAM.
